UNITED STATES PATENT OFFICE

128,940

DESIGN FOR A PENDANT TYPE HANDLE FOR STOVES OR THE LIKE

Elmer D. Pellegrin, Woodstock, Ill., assignor to
Geo. D. Roper Corporation, Rockford, Ill., a cor-
poration of Illinois

Application March 24, 1941, Serial No. 99,799

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Pendant Type Handle for Stoves or the like, of which the following is a specification, reference being had to the accompanying drawing, forming part thereof.

In the drawing:

Fig. 1 is a front view of a pendant type handle for stoves or the like showing my new design;

Fig. 2 is a top plan view thereof indicating in dotted lines the location of attaching brackets;

Fig. 3 is an end view showing the handle in normal pendant position;

Fig. 4 is an end view showing the handle swung outwardly to operative position, the attaching bracket for the handle and a limit stop on the handle for engagement with the bracket being indicated in dotted lines, and

Fig. 5 is a sectional view taken on the line 5—5 of Fig. 1 to show the cross-sectional contour of the handle at that point.

The dominant features of the design are those shown in full lines.

I claim:

The ornamental design for a pendant type handle for stoves or the like, substantially as shown and described.

ELMER D. PELLEGRIN.
